UNITED STATES PATENT OFFICE.

DAVIS L. JONES, OF MAYTON, MISSISSIPPI.

DETACHABLE POCKET.

No. 887,479.

Specification of Letters Patent.

Patented May 12, 1908.

Application filed December 20, 1907. Serial No. 407,324.

To all whom it may concern:

Be it known that I, DAVIS L. JONES, a citizen of the United States, residing at Mayton, in the county of Rankin and State 5 of Mississippi, have invented certain new and useful Improvements in a Detachable Pocket, of which the following is a specification.

This invention relates to detachable pockets for trousers especially adapted to be used by workmen, the object being to provide a pocket which can be readily slipped within an ordinary hip pocket of the trousers, so as to prevent the same from becoming worn when carrying tools therein.

Another object of my invention is to provide a pocket which is exceedingly simple and cheap in construction and one which is adapted to be supported by the belt in the 20 pocket, it of course, being understood that it can be used without the belt when desired.

Another object of my invention is to overcome the difficulties now existing with trousers as the pockets soon become worn 25 out and useless and bothersome as when things are placed therein they are lost.

These objects are obtained by the novel arrangement and construction of parts hereinafter fully described and shown in the accompanying drawings, in which,

Figure 1, is a perspective view of a pair of trousers and belt showing the application of my improved pocket, one of the pockets being removed from the hip pocket of the 35 trousers. Fig. 2, is a vertical section through the pocket and belt.

In the drawings A, indicates a pair of trousers provided with belt straps in which is arranged a belt B. The trousers being 40 provided with an ordinary hip pocket C, in which my improved detachable pockets D, are adapted to be arranged.

The pockets D, are formed of a single piece of material such as heavy cloth or leather, 45 one end of which is folded back upon itself, the edges over-lapping the edges of the main portion of the cloth and are secured thereto by rows of stitching which forms a pocket as clearly shown.

50 A pair of spaced parallel slots is formed in the main portion of the cloth above the pocket forming laps D', through which the belt is adapted to pass and it will be seen that by

sliding the belt between these straps, the pocket can be readily placed in the hip pocket 55 of a pair of trousers, whereby when heavy tools are inserted in the same the pockets will be supported by the belt and will protect the pockets of the trousers. When these pockets become worn by long use they 60 can be readily replaced by new ones thereby overcoming the difficulties of having to have new pockets put in the trousers which is the case with the trousers now in use by workmen.

65 From the foregoing description it will be seen that I have provided a detachable pocket which is simple and cheap in construction and one which is effective in use as heavy tools can be readily carried therein 70 without drawing the trousers downward.

Having thus described my invention what I claim as new and desire to secure by Letters Patent is:

1. A detachable pocket for trousers comprising a piece of material having one end portion folded upon itself, the edges of the folded back portion overlapping the edges of the main portion of the cloth and secured thereto by rows of stitching to form a pocket, 75 the main portion of the material being provided with spaced parallel slits forming straps adapted to be arranged on a belt for supporting said pocket within the pocket of an ordinary pair of trousers.

85 2. As a new article of manufacture, a detachable pocket for trousers comprising a single piece of material, folded back upon itself, to one side of its longitudinal center, forming an upwardly extending portion, the 90 edges of the folded back portion, overlapping the edges of the main portion, and stitched thereto, to form a pocket, said upwardly projecting portion being provided with a pair of spaced parallel slits forming 95 straps adapted to receive a belt for supporting said pocket within the pocket of the trousers.

In testimony whereof I have signed my name to this specification in the presence of 100 two subscribing witnesses.

DAVIS L. JONES.
